UNITED STATES PATENT OFFICE

JOHN HOLTZMAN, OF NEW YORK, N. Y.

RAZOR-BLADE EJECTOR

Original application filed July 31, 1924, Serial No. 729,283. Divided and this application filed April 9, 1927.
Serial No. 182,217.

This invention relates to a razor blade ejector, and is a division of my application for razor blade holder, filed July 31st, 1924, Serial Number 729,283.

5 The object of the invention is the production of an ejector to eject wafer razor blades from a holder.

Fig. 1 is a side view of a stopper to which my invention has been applied.

10 Fig. 2 is an end view of the same.

Fig. 3 is a vertical section taken on the line 8—8 of Fig. 2.

Fig. 4 is a similar view showing the positions of certain of the parts after the ejector 15 has been operated.

Fig. 5 is a left end view of Fig. 1, some of the parts having been removed to expose the interior construction.

Fig. 6 is a horizontal section taken on the 20 line 11—11 of Fig. 1.

Fig. 7 is a side view of a wafer safety razor blade, and

Fig. 8 is an end view of the same.

The razor blade sharpener is shown to comprise a housing with the shell 55, which has connected to its ends the heads 56 and 57. The head 57 has formed therein the depression 58, the blade opening or slot 59 and the openings 60 and 61. The head 57 has formed 25 therein the openings 62, 63 and 64. A blade holder 65 has one end fastened to the head 57 and extends into the shell 55 up to the depression 58 of the head 56, and has extending through the walls at one end thereof the stop 30 pin 66.

A segmental sharpening roll 68 with the strop 69 and the segmental sharpening roll 70 with the strop 71 are located in the shell 55 with the strops oppositely positioned. The 35 roll 68 is supported on and fastened to the driving shaft 72, which has formed therewith the journal ends 73 and 74. The journal end 73 is journaled in the journal bearing 75 fastened to the head 57 in its opening 63, and 40 the journal end 74 is journaled in the journal

bearing 76 fastened to the head 57 in its opening 60. A link 80 has one end fastened to the outer end of the journal end 74 by means of the screw 75^a and has formed at its outer end the heels 81 and 82. A second link 85 is pivot- 50 ed to the link 80 by means of the pivot 86. The link 85 has formed at one end the heel 87 and at its other end has extending therefrom the operating handle 88. A gear 90 is location in the shell 55 and is fastened to the 55 roll 68 adjacent to the head 57.

The sharpening roll 70 has axially located therein the sleeve 91. A shaft 92 rotatively supports the sleeve 91 and is fastened to the heads 56 and 57 by means of the screws 93. 60 A spur gear 94 is fastened to the roll 70 adjacent to the head 57.

An ejector bar 98 extends through the opening 62 in the head 57 and extends into the blade holder 65. An elongated guide open- 65 ing 100 is formed in the bar 98, which engages the stop pin 66. An operating finger piece or disc 101 extends from the outer end of the bar 98.

A razor blade 102 is shown with the single 70 cutting edge 103.

To operate the razor blade sharpener the razor blade 102 is pushed through the opening 59 into the holder 65, in which it is loosely supported to the position indicated in Fig. 75 8 and one end thereof bears against the adjacent end of the bar 98 after the latter is pulled out of the shell 55 until the inner end of the opening 100 bears against the stop pin 66. The handle 98 is now revolved in the 80 direction of the arrow A (Fig. 2). By this means the roll 68 turns a little more than one half of a revolution in one direction and then the roll 70 begins to turn in an opposite direction. The strops 69 and 71 alternately 85 bear against the sides of the cutting edge of the razor blade 102, and sharpen the same. On account of the razor blade being loosely supported in the holder 65, the said blade is alternately moved by the rolls into slightly 90

inclined positions to alternately sharpen the opposite sides of its cutting edge. When the operating handle 88 is revolved in the direction of the arrow A, the heels 82 and 87 bear against each other and the links 80 and 85 are maintained with their longitudinal axial lines coincident, and the rolls are turned. If the operating handle is attempted to be revolved in a direction opposite to the arrow A, the opposite face of the heel 87 bears against the heel 81 and the energy of revolution takes the direction of the dotted line C, D (Fig. 2) and the sharpening rolls do not rotate. By means of this construction the strops are prevented from being cut by the razor blade.

After the razor blade has been sharpened it is ejected from the housing by pushing in the bar 98.

The function of the ejecting bar 98 is quite important, as the removal of the blade 102 from the holder 65 may be accomplished without handling the blade, thereby facilitating its removal and preventing injury to its fine cutting edge. It is to be understood that the ejector device, which is in this application applied to a stropping device is not limited to this particular embodiment. Various modifications may be made in the invention and the present exemplification is to be taken as illustrative and not limitative thereof.

Having described my invention what I desire to secure by Letters Patent and claim is:

1. In ejecting means for wafer safety razor blades, a casing, a member within the casing adapted to position safety razor blades, a blade ejector member arranged for movement into and out of the casing, and arranged to engage and to push upon the end of a blade to eject the blade from the casing, one of said members having a slot therein, and a pin in the other of said members inserted into the slot for limiting the movement of the ejector member.
2. In a device for ejecting wafer safety razor blades, the combination of a casing having a slotted passage at one of its ends, a stationary blade holding member fixedly mounted within the casing, a reciprocatory ejector member supported against longitudinal tilting movement for propelling a razor blade through the slotted passage and out of the casing, said ejector member being permanently inserted through an opening in the other end of the casing, a pin carried by one of said members and entering a slot in the other of said members for guiding and limiting the outward movement of said ejector member and a finger-piece mounted on said ejector member to actuate the same.
3. In a device for ejecting safety razor blades, the combination of a casing member, having a slot at one end thereof, for the passage of a safety razor blade, a blade positioning member secured against movement in any

direction within said casing member, means for ejecting said blade out of said casing member, said means including a reciprocatory ejector member snugly fitted into said casing member, a slot and pin connection between the ejector member and one of the other of said members for limiting the movement of said ejector member and a finger-piece on said ejector member to manipulate the same.

In testimony whereof I affix my signature.

JOHN HOLTZMAN.
